UNITED STATES PATENT OFFICE.

HART HARRIS, OF WASHINGTON, PENNSYLVANIA.

DESIGN FOR A CAN-OPENER.

SPECIFICATION forming part of Design No. 29,508, dated October 18, 1898.

Application filed September 26, 1898. Serial No. 691,938. Term of patent 14 years.

To all whom it may concern:

Be it known that I, HART HARRIS, a citizen of the United States, residing at Washington, in the county of Washington and State of Pennsylvania, have invented and produced a new and original Design for a Can-Opener, of which the following is a specification.

This invention relates to a new and original design for a can-opener; and it has for its object to provide a design of this character that shall be both useful and ornamental.

The leading feature of the design resides in a can-opener provided with an approximately elliptical blade having one of its faces transversely convexed and sloping to the edges of the blade.

The minor feature of the design is the opener, having a handle-shank provided with a substantially right-angular shoulder portion and having the blade projected beyond said shoulder in a plane approximately parallel to the main part of the shank.

An additional minor feature may be said to be the blade, having its face opposite the convexed face substantially flat and curved slightly longitudinally of the blade.

In the drawings, Figure 1 is a perspective view of a can-opener embodying the herein-described design. Fig. 2 is a plan view thereof. Fig. 3 is a side view. Fig. 4 is a transverse sectional view of the blade on the line 4 4 of Fig. 2.

Referring to the accompanying drawings, the numeral 1 designates the straight handle-shank of the opener, having thereon a longitudinal hand-grasp or handle 2 and provided beyond said hand-grasp or handle with a substantially right-angular shoulder portion 3. Beyond the shoulder portion 3 the shank 1 is laterally widened to form the blade 4, which projects beyond the shoulder 3 in a plane substantially parallel to the main portion of the shank, and said blade 4 is of an approximately elliptical shape with a blunt rounding point 5. The said elliptical blade 4 has one of its faces (designated by the numeral 6) convexed. The transversely convexed face 6 is rounded and slopes to the edges of the blade, and at the side opposite the convexed rounded face 6 the said blade is provided with a substantially flat face or surface 7, which has a slight curvature longitudinally of the blade.

What is claimed is—

The design for a can-opener, herein shown and described.

In testimony that I claim the foregoing as my own I have hereto affixed my signature in the presence of two witnesses.

HART HARRIS.
